Patented May 15, 1973

226,907

COMBINED SNOW AND WATER VEHICLE

Robert V. Albertson, Wayzata, Minn., assignor to
Massey-Ferguson Inc., Detroit, Mich.

Filed July 12, 1971, Ser. No. 161,382

Term of patent 14 years

Int. Cl. D12—14, 06

U.S. Cl. D14—24

Fig. 1

Fig. 2

Fig. 3

Fig. 4

FIG. 1 is a perspective view of a combined snow and water vehicle embodying my new design and taken generally from the front and left side thereof;

FIG. 2 is a perspective view of a combined snow and water vehicle taken from the right side thereof;

FIG. 3 is a perspective view of a combined snow and water vehicle taken generally from the front and right side thereof; and

FIG. 4 is a perspective view of a combined snow and water vehicle taken generally from the rear and right side thereof.

I claim:
The ornamental design for a combined snow and water vehicle, substantially as shown.
